NONsinkable BATHING SUIT

Albert L. Sommers and Anna M. Littger, Newburgh, N. Y., assignors of five percent to Robert Block, Newburgh, N. Y.

Application January 3, 1939, Serial No. 249,086

2 Claims. (Cl. 9—20)

This invention relates to a nonsinkable bathing suit.

An object of the invention is the construction of a bathing suit which is very buoyant, and warm when in actual use.

Another object of the invention is the construction of a novel and efficient fabric for use in the construction of any form or style of a bathing suit, or any unit thereof, since it is common to form bathing suits today in two-piece styles or forms.

A still further object of the invention is the construction of the fiber of a bathing suit of twisted tubings of warm material, and within the tubings between each two twists we place a very buoyant and water-proof capsule, whereby the finished article is exceedingly buoyant.

With the foregoing and other objects in view, the invention comprises certain novel constructions, combinations, and arrangements of parts that will be hereinafter fully described, illustrated in the accompanying drawing, and more particularly pointed out in the appended claims.

In the drawing:

25 Figure 1 indicates by dotted lines a bathing suit of any form or style, with the fabric thereof shown in full lines.

Figure 2 is an enlarged detailed plan view of the fabric constructed in accordance with the 30 present invention.

Figure 3 is an enlarged fragmentary sectional view of a wool tubing showing Celluloid capsules in spaced position therein.

Figure 4 is an enlarged view in elevation of 35 a portion of the tubing, ready to be woven, as a part of the fabric.

Figure 5 is an enlarged transverse sectional view of one of the Celluloid capsules.

Figure 6 is an enlarged view of the Celluloid 40 capsule, partly in elevation and partly in section.

Figure 7 is an enlarged view showing the manner of twisting or fastening two separate tubings together, during the process of weaving the 45 fabric.

Referring to the drawing by numerals, the dotted line designated by 1 indicates any style or form or shape of a bathing suit that may be constructed in accordance with this invention.

50 The woven or mesh fabric 2, of which the suit is constructed is formed out of fibrous-material tubings 3 (Fig. 3); which tubings in our preferred construction are formed of wool. We preferably use wool because it is strong, light, and warm. Spaced within the wool tubing 3

are hollow capsules 4, these capsules 4 being preferably formed of specially-treated Celluloid, whereby liquid, such as water, does not affect same, with reference to deterioration or their buoyancy. Each capsule 4 is preferably formed in sections, as indicated in the large view, Fig. 6. These sections are cemented together with heat. The capsules may be formed of other non-sinkable materials, treated for making them absolutely water-proof.

5 The wool tubings 3 are preferably twisted at 5 (Fig. 4), and within each two contiguous twisted portions is placed one of the capsules 4.

After the wool tubings 3, containing the capsules, have been twisted they are woven or fastened together at their twisted portions, as is clearly shown in Figures 1, 2 and 7. Therefore, it will be seen that the weaving together of the fabric may be caused by twisting or inter-fastening the tubings at their crossed twisted portions, or if the operator desires, they may be laid together in their crossed position, at the twisted portions, and sewed together.

The woven fabric, in accordance with our invention, forms a substantially close net or weave when placed on the body, and as the bathing suits are worn in comparatively warm or hot weather, the wearing will prove highly satisfactory, because the suit is substantially a woolen structure, which will give warmth and keep the 30 bather from chilling when out of the water. When in the water, the buoyancy of the bathing suit will result in great pleasure to the wearer, especially to those persons not able to swim, and will also act as a life-preserved for every person 35 wearing a suit of our construction.

Our bathing suit is not cumbersome; it is compact, as well as attractive. It acts both as a bathing suit and a life-preserved, whereby it doubly increases its value over an old-type bathing suit. The method of constructing our bathing suit is equally appropriate for a single-piece suit, or a two-unit suit, such as a trunk and a shirt suit.

In Figure 7, we have shown how the "weaving" of the hollow fabric tubings may be carried out; the crossed, twisted portions are interlaced or woven together, thereby adequately securing the tubings in their woven or "knitted" 45 positions, for producing the new fabric as clearly 50 shown in Figure 1.

While the preferred embodiment of this invention has been described and illustrated in the accompanying drawing, certain minor changes or alterations may appear to one skilled in the 55

art to which this invention relates during the extensive manufacture of same, and, therefore, we reserve the right to make such changes or alterations as shall fairly fall within the scope 5 of the appended claims.

What we claim is:

1. A woven fabric nonsinkable bathing suit, comprising longitudinally and transversely-extending tubings, each tubing being provided with 10 spaced buoyant units therein, and said longitudinally and transversely-extending tubings se-

cured together only between the contiguous ends of the buoyant units.

2. A nonsinkable fabric for bathing suits, comprising wool tubings, Celluloid capsules in spaced position within each tubing, each tubing twisted throughout its length between the contiguous ends of said capsules, and said tubings interlaced at their twisted portions between contiguous ends of the capsules. 5

ALBERT L. SOMMERS. 10
